UNITED STATES PATENT OFFICE.

ELIJAH F. STEELE, OF WALLINGFORD, CONNECTICUT.

IMPROVEMENT IN SAFETY-VALVES FOR STEAM-BOILERS.

Specification forming part of Letters Patent No. **147,292**, dated February 10, 1874; application filed January 9, 1874.

To all whom it may concern:

Be it known that I, ELIJAH F. STEELE, of the town of Wallingford, in the county of New Haven and State of Connecticut, have invented certain Improvements in Safety-Valves for Steam-Boilers, of which the following is a specification:

The object of this invention is to furnish a valve which shall be sensitive to slight changes in the pressure of the steam, and of compact form, which causes it to be very suitable for use upon locomotive-boilers or those of portable engines. The invention consists in an arrangement of two valves connected by a stem or rod, a spiral spring, a sleeve incasing the spring and part of the valve-stem, and an adjustable nut or cap, all constructed and operating together as hereinafter fully described.

The drawing is a-sectional view of the invention, with the valves open for the escape of steam.

A represents the case, forming a hollow globe, with suitable chambers for the passage of the steam. B B' are the valves, nearly equal in size, the surface of the valve B being so much increased as to give it sufficient lifting power, under ordinary pressures, to lift both valves with the stem and its connections. C C' are the valve-seats, and D is the valve stem or rod, around the upper part of which is coiled the spiral spring E; it is also provided, at its upper end, with a scale and ring, K, by which the valve may be raised when desired. The cap or nut F is screwed upon the sleeve G, and is used to regulate the tension of the spring, also serving as a stop for the valves at G'. This sleeve, containing the spiral spring and valve-stem, forms part of a plate, L, which is secured to the case A by screw-bolts. H is the opening to which the steam-pipe leading from the boiler is attached. I is the opening for a pipe leading to the engine, and J is the

escape-pipe. The scale and figures on the valve-stem form an index for setting the valve to any desired pressure by screwing down the adjustable cap F until its upper surface is in line with the figures on the stem, which indicates the pressure required. The arrows indicate the course of the steam in passing through the valve.

By means of this arrangement, I am enabled to dispense with the levers and great weights, usual in ordinary safety-valves, to insure more speedy relief of the pressure upon the boiler, to adjust the valve easily so as to discharge at a given pressure, and to diminish the danger of the valves being broken or stuck down by any sudden and violent closing.

In operation, it will be seen, the valve B being larger than B', the valves are raised and opened by the excess of pressure of the steam upon B over that upon B'. The spiral spring E acts with B' to keep the valve closed. This spring is adjusted by the nut F, according to the index on the valve-stem, to resist any required pressure, so that the valves open when the pressure upon the valve B exceeds the resistance of the spring and valve B'.

Having thus described my invention, I claim as new and desire to secure by Letters Patent—

The combination of the case A, provided with the openings H I J, and the plate L, provided with the sleeve G, the valves B B', the valve-stem D, cap F, and spring E, substantially as and for the purpose hereinbefore set forth.

In testimony that I claim the foregoing, I have hereunto set my hand this 26th day of December, 1873.

ELIJAH F. STEELE.

In presence of—

JUDAH FRISBIE,
HENRY E. PARDU.
